UNITED STATES PATENT OFFICE

2,589,516

BAR MOUNTING

Otto E. Stelzer, South Bend, Ind.

Application September 1, 1948, Serial No. 47,293

10 Claims. (Cl. 16—1)

1

This invention relates to improvements in bar mountings, and more particularly to a device for mounting a bar for use as a door pull, as a towel bar, or as a part of a household fixture.

The primary object is to provide a novel, simple and inexpensive device of this character which is easily installed and assembled, whose securing means are camouflaged or concealed, which supports a bar firmly and securely, and which may have any desired decorative appearance.

A further object is to provide a device of this character adapted for use as a door pull in conjunction with a similar device located at the opposite side of a door, wherein the parts are secured together in clamping engagement with the door by a single securing member accessible at the interior of the door and concealed, so that the device cannot be tampered with, or part or all thereof removed or disassembled by an individual located at the exterior of the door.

A further object is to provide a device of this character, including a pair of cylindrical members adapted for end abutment with a supporting surface, said cylindrical members having a series of circumferential grooves and at least one member mounting a concentric end part whose junction therewith is not discernible by reason of the similarity of the appearance of the line of junction to the appearance of said grooves, said members having sockets to snugly receive and support opposite ends of a bar extending therebetween.

A further object is to provide a device of this character wherein a pair of rigid similar elongated hollow members are adapted for end abutment with a support and are provided with transverse bar-receiving apertures, said members extending through transverse apertures in the bar to hold the bar against longitudinal and rotative movement.

Other objects will be apparent from the following specification.

In the drawing:

Fig. 1 is a side view of one embodiment of the invention with parts thereof shown in axial section.

Fig. 2 is a fragmentary axial sectional view of a modified embodiment of the invention.

Fig. 3 is an axial sectional view of another embodiment of the invention.

Referring to the drawing which illustrates the invention as used for the purpose of mounting bars upon a door to serve as door pulls, and referring particularly to Fig. 1 thereof, the numeral 10 designates a door panel which is provided with a pair of spaced openings 12 extending therethrough. The invention is particularly

2

adapted for use in conjunction with a solid glass door, and as here illustrated the door panel 10 is illustrated as being formed of glass. It will be understood, however, that the device may be used in conjunction with a door formed of any material desired. It will be assumed in each instance that the surface of the door panel 10, positioned lowermost in the figures, is the outer door surface, and that the surface positioned uppermost in said figure is the inner surface of the door.

In the embodiment illustrated in Fig. 1, a pair of cylindrical members 14, preferably formed of metal such as aluminum, are mounted in register with the openings 12 of the door at the outer surface thereof, the same preferably bearing against gaskets 16 interposed between the same and the surface of the door. The cylindrical members are preferably formed of solid bar material as shown, and at their inner ends each is preferably provided with a central longitudinal internally screw-threaded bore 18. Adjacent its outer end each member has a socket 20 formed therein extending transversely thereof and an outer door pull bar 22 at its opposite end portions seated snugly in the sockets 20.

Cylindrical cup-shaped elongated members 24 having an axial cavity 26 and whose external dimensions are preferably substantially the same as the dimensions of the members 14, bear against the inner surface of the door panel 10 or against gasket members 28 interposed between the end of the same and said door panel. The base portion 30 of each member 24 has a central opening formed therein and a screw-threaded member 32 extends therethrough and through the gasket 28 or the opening 12 of the door panel 10, the gasket 16, and is threaded into the socket 18 of the member 14. Each screw is provided with an enlarged head 34 which seats against the base 30 and permits the parts to be drawn together for firm end abutment of the members 14 and 24 with the opposite surfaces of the door panel 10. In the preferred embodiment of the invention, the openings 12 in the door panel are preferably of larger diameter than the diameter of the bolt 32, and an annular gasket member 36 having an outer dimension to fit snugly in the opening 12, and an inner dimension to fit snugly around the bolt, is inserted in the door opening. The member 36 is preferably of slightly greater normal length than the thickness of the door panel 10; consequently as the members 14 and 24 are drawn together by the bolt 32, the member 36 is compressed longitudinally and expanded laterally to insure a snug fit of the parts and to prevent free play of the members 14 and 24 transverse of their axes.

Each of the members 24 has a transverse socket 38 formed therein adjacent its outer end, and these sockets receive the outer end portions of a door pull bar 40.

The outer end of the cavity 26 of each member 24 is internally screw-threaded at 42 to receive a screw-threaded projection 44 extending from a closure or cap 46 whose outer diameter is preferably equal to the outer diameter of the member 24. In the embodiment of the invention shown, the margin of the closure member 46 at its inner portion is beveled at 48, and the upper or outer margin of the member 24 is similarly beveled at 50. The two bevels 48 and 50 provide at the line of separation between the closure 46 and the members 24 a shallow V-shaped circumferential groove. At one or more longitudinal points along each of the members 24 are formed circumferential grooves 52, preferably of the same size and shape as the groove formed by the beveled faces 48 and 50. Similar circumferential grooves 54 may be formed in the members 14 if desired. By reason of the provision of the grooves 52 and the matching thereof with the grooves defined in the bevel edges 48 and 50, the line of separation between the closures 46 and the members 24 is camouflaged or concealed so that when the closures 46 have been drawn tight to eliminate any free play or rotation thereof, the manner by which the members 24 and 14 are secured to the door is completely concealed. This insures against tampering, as by children, and prevents any possible occurrence of partial or complete disassembly of the door pull. Inasmuch as the outer members 14 which mount the outer door pull part 22 are concealed, no possibility exists, without complete breakage of the members 14, of removing the same from the exterior of the door.

Fig. 2 illustrates another embodiment of the door pull of different construction. In this instance the members 60 mounting both the inner bars 40 and the outer bars 22 are of similar construction and are preferably tubes whose inner ends bear against the opposite surfaces of the door panel 10 in substantially axial alignment or bear against gasket members 62 interposed between the same and said door. An annular resilient positioning member 65 is seated snugly in each opening 12, and an elongated rod 64 extends therethrough and projects at its opposite end substantially the full length of each of the members 60. Closure plates 66 are provided with reduced dimension inner portions 68 fitting snugly within the tubes 60 and are shouldered at 70 to bear against the outer ends of said tubes. The inner faces of the closures 66 are provided with central screw-threaded sockets 72, and the opposite end portions 74 of the bar 64 are screw-threaded for reception in said socket 72. The threading of the closure 66 onto the threaded end 74 of the bar 64 serves to draw the members 60 firmly against the opposite faces of the door panel 10 and to hold the device in assembled position.

The tubular members are provided with a transverse aperture 76 of a size to snugly receive the associated one of the bars 22 and 40. These bars are of a length to extend into and substantially across the interior of the members 60 and are provided at the portions thereof within said members 60 with a transverse passage 78 having a free sliding fit around the bar 64. It will be apparent that in this embodiment of the invention, the two bars 40 and 22 are held firmly

against both endwise movement and rotative movement. The adjustment of the parts to effect their assembly is accomplished easily by applying the member 64 to the door and then applying the members 60 and their associated parts as a unit around the bar 64 into end abutment with the door panel, following which the closure 66 may be applied.

A third embodiment of the invention applicable for use as a door pull, wherein the bars 22 and 40 are mounted at the outer and inner sides, respectively, of a door panel 10 provided with apertures 12, is illustrated in Fig. 3. In this embodiment of the invention the bar mounting members 80 are preferably similar, being of tubular construction and having inwardly projecting flanges 82 at their inner ends adapted for abutment with the opposite faces of the door panel 10 or with gaskets interposed between the same and said door panel. A resilient annular gasket member 84 is located within each door opening 12 as in the other embodiments, but preferably is of a length equal to the thickness of the door panel 10 plus the thickness of the two flanges 82. Circular plates 86 fit within the members 80 and bear against the outer surfaces of the flanges 82. A bolt 88 has an enlarged head 90 bearing against one of the plates 86 and having screw-threaded engagement with the opposite plate 86, the shank of said bolt passing snugly through the resilient member 84 and serving to longitudinally compress said member as the parts are drawn to fully secured and firmly anchored position.

Each of the members 80 has a transverse opening 92 adjacent its outer end to snugly receive the end of the adjacent one of the bars 22 and 40. The bars 22 and 40 are each of a length to project into the members 80 in intersecting relation to the axis thereof and are provided with internally screw-threaded transverse sockets or bores 94 substantially axially aligned with said members 80. Closure plates 96 bear against the outer ends of the tubes 80 and mount central inwardly projecting screw-threaded studs 98 which may be threaded into the sockets 94 to hold the closure plates upon the members 80. At the same time the threaded engagement of the closure studs with the respective bars 22 and 40 hold said bars against endwise movement and against rotative movement.

In each of the embodiments shown in Figs. 2 and 3, the members 60 and 80, respectively, may be provided with one or more circumferential grooves 64 and 84, respectively, so shaped and positioned as to conceal the line of separation of the closures mounted upon the outer ends of said bars in the same manner more particularly described above with reference to the construction shown in Fig. 1.

While the invention has been illustrated herein as embodied in the door pull unit, its use is not limited thereto, and the construction may be utilized for other purposes, such as use as a towel bar or the like. In such uses only that part of the device illustrated above the panel 10 in the drawing will be employed. Thus it will be apparent that the bolt 32 of the Fig. 1 embodiment may be replaced by a wood screw or the like adapted to be anchored in a wall, molding or other support, for the purpose of positioning the two members in operative relation to said support for the purpose of mounting the bar 40. Similarly, the bolt 88 in Fig. 3 may be replaced by a screw or other securing member adapted to secure a member 80 to a support. The adap-

tation of the construction illustrated in Fig. 2 requires a slight change therein, specifically the fixed anchoring of a bar or stud 64 to the wall before the Fig. 2 construction can be assembled and mounted upon the wall.

While the preferred embodiments of the invention have been illustrated and described herein, it will be understood that changes may be made therein within the scope of the appended claims without departing from the spirit of the invention.

I claim:

1. A device of the character described, comprising a bar, a pair of similar elongated members adapted for end abutment with a support, each elongated member having a transverse socket intermediate its ends adapted to receive an end of said bar and a central cavity open at its outer end, a securing member adapted to secure each elongated member to said support and extending into and accessible at said cavity, and a closure for said cavity removably mounted on each elongated member, said securing member extending lengthwise in said cavity and having a screw-threaded end portion, said closure having a screw-threaded socket receiving the threaded end of said securing member.

2. A device of the character described, comprising a bar, a pair of similar elongated members adapted for end abutment with a support, each elongated member having a transverse socket intermediate its ends adapted to receive an end of said bar and a central cavity open at its outer end, a securing member adapted to secure each elongated member to said support and extending into and accessible at said cavity, and a closure for said cavity removably mounted on each elongated member, said securing member extending lengthwise in said cavity and having a screw-threaded end portion, said closure having a screw-threaded socket receiving the threaded end of said securing member, said bar projecting into said cavity and having a transverse passage receiving said securing member.

3. A door pull for a door having a pair of apertures comprising two pairs of elongated members, the members of each pair being adapted for end abutment with one surface of a door in substantial alignment with the members of the opposite pair, a pair of bars, each member having a transverse socket intermediate its ends to receive an end portion of a bar and position the same in spaced substantially parallel relation to said door, the members of one pair each having a central cavity open at its outer end, resilient sleeves adapted to seat snugly in said door apertures securing units accessible through said cavities and extending through said sleeves for securing anchorage with the members of the pair at the opposite side of said door, and a closure removably mounted on the end of each cavitated member.

4. In combination, a door having a pair of spaced openings therethrough, two pairs of elongated members, the members of each pair being adapted for end abutment with one surface of said door in alignment with said openings and with the members of the opposite pair, a pair of bars, each member having a transverse socket intermediate its ends to receive an end portion of one bar and position the same in spaced substantially parallel relation to said door, the members of one pair being cup-shaped with their base portions positioned innermost, securing members accessible through said cup-shaped

members and extending through said openings for anchorage with the members of the other pair, a yielding member positioned snugly in each opening and encircling a securing member, each yielding member having a length greater than the thickness of said door to be longitudinally compressed and laterally expanded when said securing members draw said first named members toward each other, and closures removably mounted on the outer ends of said cup-shaped members.

5. A door pull as defined in claim 3, wherein said elongated members and closures are cylindrical and said closures are of the same diameter, at least said cavitated members having a circumferential groove simulating the line of separation between the same and its closure.

6. The combination defined in claim 4, wherein all of said elongated members are hollow, said bars having transverse sockets at their end portions, and studs projecting inwardly from said closures and seated in the sockets in said bars.

7. The combination defined in claim 4, wherein said elongated members are hollow and said sockets constitute openings, the end portions of said bars projecting into said hollow members and having transverse threaded sockets coaxial with said closures, each hollow member mounting a closure, and screw threaded studs projecting centrally inwardly from said closures and received in said threaded sockets.

8. The combination defined in claim 4, wherein each elongated member constitutes a tube having an interior shoulder at its inner end, a plate in each tube bearing against said shoulder, said securing members connecting the plates of aligned tubes, each member having a closure at its outer end, and threaded studs carried by said closures and having screw-threaded connection with the adjacent end of a bar.

9. A door pull as defined in claim 3, wherein said elongated members are tubular and each mounts a closure bearing against its outer end, each closure having a screw-threaded socket open at its inner face, said securing members each comprising an elongated stud screw-threaded at both ends and received in the sockets of said closures.

10. A door pull as defined in claim 3, wherein said elongated members are tubular and each mounts a closure bearing against its outer end, each closure having a screw-threaded socket open at its inner face, said securing members each comprising an elongated stud screw-threaded at both ends and received in the sockets of said closures, the end portions of said bars projecting into said tubular members and each having a transverse passage therethrough receiving a securing member.
